(57) **CLAIM**

The ornamental design for a portion of a vehicle as shown and described.

DESCRIPTION

FIG. 1 is a front perspective view of a portion of a vehicle showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front top perspective view thereof;

FIG. 9 is a front bottom perspective view thereof;

FIG. 10 is a rear bottom perspective view thereof; and,

FIG. 11 is a rear top perspective view thereof.

The even length broken lines depict portions of the vehicle that form no part of the claimed design. The dash-dot broken lines depict the claim boundary and form no part of the claimed design. As an example, the design may be implemented as a portion of a toy replica of a vehicle.
